UNITED STATES PATENT OFFICE.

CAMILLE DUQUENNE, OF PARIS, FRANCE.

BOILER.

1,411,880.

Specification of Letters Patent. Patented Apr. 4, 1922.

Application filed April 11, 1919. Serial No. 289,421.

To all whom it may concern:

Be it known that I, CAMILLE DUQUENNE, a citizen of the Republic of France, and a resident of 6 Rue d'Ulm, Paris, France, 5 have invented new and useful Improvements in and Relating to Boilers, of which the following is a specification.

The present invention relates to a boiler of the type comprising vaporizing elements 10 each formed of a group of straight tubes, vertical or almost vertical, secured at their extremities in collectors of headers, the upper header of each element being connected with the drum of the boiler, and the lower 15 header connected with the water-return collector by means of nipples, which allow of very rapid mounting and dismounting.

The steam-boiler forming the subject of the present invention is characterized by 20 the fact that a longitudinal partition divides the superheating tubes and the greater part of the vaporizing tubes from the direct action of the fire, this partition stopping at a certain distance from the rear wall supporting 25 the boiler, so that the products of combustion circulate from front to rear, first heating only the directly flame-licked tubes or fire-box tubes of the vaporizing groups, and then coming round towards the front 30 between this partition and the corresponding outside lateral wall of the boiler casing and heating the other vaporizing tubes and the superheating tubes.

The annexed drawing shows by way of 35 example one form of carrying out the invention as applied to a marine boiler.

Figs. 1 and 1^a show two half sections transversely in different vertical planes; Fig. 1 through a superheating element and 40 Fig. 1^a through a vaporizing element respectively following line 1—1 and line 1^a—1^a of Fig. 2;

Fig. 2 shows diagrammatically, on a smaller scale, a section through line 2—2 45 of Figs. 1 and 1^a.

The boiler consists of an upper drum *a* connected at each of its extremities by two water-return tubes or downcomers *a*¹, *a*¹ and *a*², *a*² to two collectors or boxes *b*, *b*. The 50 vaporizing elements are composed of banks or groups of straight tubes *c*, *c* very slightly inclined relatively to the vertical, which are expanded at their extremities into headers or collectors of square sections *d* and *e*; the 55 lower header *d* of each unit is connected with the corresponding water-return chamber or

box *b* by a nipple or pipe *f* having a coned metal-to-metal joint, an oval flange *f*¹ slideable freely on the pipe, ensuring the fastening by means of two bolts. The upper 60 header *e* of each vaporizing element is also connected with the drum *a* of the boiler by a nipple *e*¹ of the same kind with two securing flanges *e*², *e*² connected by two bolts. Each vaporizing element is thus dismountable 65 by removing four bolts; these elements are made to gauge or standardized in such a way as to be interchangeable.

Opposite each open end of the tubes *c*, *c*, are arranged upon the headers *d* and *e*, 70 screw plugs *c*¹, *c*¹, having metallo-plastic joints upon milled surfaces permitting the cleaning or the replacing of each tube.

The superheating elements, shown on the left half of Fig. 1 and in Figs. 2 and 3, 75 comprise each a number of tubes *g*, the extremities of which are connected to the front and rear parts of the corresponding upper header or collector *e*³, which is for this purpose divided into two compartments by a 80 partition *e*⁴. The collecting header *e*³ for the tubes of each superheating element is bolted or otherwise connected to the upper collecting header *e* of the corresponding vaporizer; in this portion of the bank of tubes, 85 these vaporizing elements consist merely of the fire-box tubes *h* receiving the direct heat of the flames and separated from the superheater tubes *g* by a thin longitudinal partition of carborundum *i* supporting or resting upon the tubes *h*; the same is the case 90 in the vaporizing elements, as shown in Fig. 1. These partitions *i*, *i* stop at a certain distance from the rear face of the boiler (see Figs. 2 and 3) so that the combustion gases 95 are passed from the front to the rear of the boiler between these partitions *i*, *i* which at the rear allow the products of combustion to pass through breaks or openings, the gases then coming around towards the front 100 between these partitions and the exterior walls of the masonry or casing and coming into contact with the tubular elements before escaping at the front by the smoke flue. According to the location of the superheat- 105

ing elements in the direction of the length of the boiler, the products of combustion will act upon the superheating tubes *g* after having traversed a path of varying length, and while still at a more or less high temperature; after the boiler has been constructed, the degree of superheat can be 110

regulated once for all according to the working conditions of the boiler in each individual case, by varying the location of these superheating tubes *g*. This operation 5 presents no difficulty, since a group of vaporizing tubes *c* as in Fig. 1^a is simply replaced by a group of superheating tubes *g*, connected to a group of fire-box tubes *h* as in Fig. 1, and vice versa. The lower part 10 of the drum *a*, as well as the connecting nipples of the upper headers *e*, are protected from heat-radiations by lagging of asbestos or by carborundum fittings *j*.

The water and saturated or wet steam 15 rises in the vaporizing tubes, and the wet steam passes into the drum *a* where the steam is separated from water; the water descends by the return tubes or downcomers *a¹*, *a²* at front and rear into the lower water- 20 chambers or boxes *b*, *b*, whence it again rises into the vaporizing elements, the fire-box tubes *h* being first supplied.

At the lower part of the water-return tubes are arranged two pockets *l* at the bottom of which are the bottom drawoff cocks. 25 The water feed takes place into the front water-return tubes *a¹*.

Steam collected into the drum *a* by a longitudinal pipe *a³* perforated with holes and 30 arranged at the upper part of this drum makes exit from this pipe by a steam valve *a⁴* and passes through the superheating elements *g*, whence it is afterwards sent into the main steam receiver; for this purpose 35 the upper collecting header *e³* of each superheating element is connected at one end to a steam intake manifold *g¹* and at its other end to a superheated steam delivery manifold *g²*; the manifolds *g¹* situated on 40 either side of the main drum *a*, are connected by the tubes *k¹* to the steam valve *a⁴* receiving the steam from the dome *a⁵*, whilst the delivery manifolds *g²* located on either side of the drum *a* are connected by the tubes 45 *k²* to the main steam collector *k*.

I claim—

1. A boiler comprising a drum arranged in the upper portion thereof, upper and lower collecting headers, groups of vaporizing tubes extending between and mounted in said headers, means for connecting the upper header to the drum, downcomers connecting the lower header of each vaporizing tube group with the drum, groups of superheating tubes extending over only a portion of the length of the boiler, an upper header for each group of superheating tubes and

extending over only a portion of the length of the headers for the vaporizing tubes, means for connecting each of said upper headers for the superheating tubes to the upper headers of the corresponding group of vaporizing tubes, a longitudinal partition protecting the superheating tubes and the greater part of the vaporizing tubes 60 from the direct action of the fire, said partition stopping at a certain distance from the rear wall of the boiler chamber, so that the products of combustion circulate from front to rear, first heating only the directly 65 flame-heated tubes of the vaporizing groups, and then coming around toward the front between this partition and the lateral wall of the boiler chamber and there heating the other vaporizing tubes and the superheating 70 tubes.

2. A boiler comprising a drum arranged in the upper portion thereof, upper and lower collecting headers, groups of vaporizing tubes extending between and mounted in 80 said headers, means for detachably connecting the upper header of each group to the drum, downcomers detachably connecting the lower header of each vaporizing tube group with the drum, groups of superheating tubes extending over only a portion of the length of the boiler, an upper header for each group of superheating tubes and extending over only a portion of the length of the headers for the vaporizing tubes, 85 means for detachably connecting each of said upper headers for the superheating tubes to the upper headers of the corresponding group of vaporizing tubes, a longitudinal partition protecting the superheating tubes and the greater part of the vaporizing tubes from the direct action of the fire, said partition stopping at a certain distance from the rear wall of the boiler chamber, so that the products of combustion 90 circulate from front to rear, first heating only the directly flame-heated tubes of the vaporizing groups, and then coming around toward the front between this partition and the lateral wall of the boiler chamber and 95 there heating the other vaporizing tubes and the superheating tubes.

In testimony whereof I have signed my name to this specification.

CAMILLE DUQUENNE.
